DESIGN FOR A CHRISTMAS STOCKING

Justin I. Kingson, Mount Vernon, N. Y., assignor to Millburn Mills, Inc., New York, N. Y., a corporation of New York

Application April 8, 1941, Serial No. 100,226

Term of patent 3½ years

To all whom it may concern:

Be it known that I, Justin I. Kingson, a citizen of the United States, residing at 6 Central Parkway, city of Mount Vernon, Westchester County, State of New York, have invented a new, original, and ornamental Design for a Christmas Stocking, of which the following is a specification, reference being had to the accompanying drawing, forming part thereof.

I claim:

The ornamental design for a Christmas stocking, substantially as shown.

JUSTIN I. KINGSON.
